ABSTRACT OF THE DISCLOSURE

A diaphragm arrangement, essentially comprising an aperture diaphragm with two diaphragm plates, for use in an X-ray diffractometer, wherein the surface of a rotatable specimen is intended to be fully scanned, whereby the movement of the diaphragm plane is synchronous with the movement of the specimen, so that the diaphragm plane is invariably at right angles to the surface of the specimen.

The invention relates to an automatic aperture diaphragm for X-ray exposures of diffraction diagrams, using a diffractometer (counting tube goniometer).

When making exposures of X-ray diagrams with a diffractometer, the intensity of the interferences decreases considerably with increasing diffraction angle 2θ . The hitherto usual aperture diaphragms having two diaphragm plates remain stationary during the exposure, whereby the cross-section of the pencil of X-rays incident on the preparation remains unchanged. In this case, therefore, always the same X-ray intensity is used. On account of the θ -movement of the preparation, the surface irradiated by the X-ray becomes smaller by $1/\sin \theta$ as the incidence angle θ increases. As a result, an always smaller number of crystallites diffracts intensity into the interferences and increases the random fluctuations of the intensity on account of a small number of effective crystallites, i.e., the influence of crystal statistics. Consequently, in order to produce a satisfactory diffraction diagram, it was formerly frequently necessary to expose several component regions of the diffraction diaphragm with a different setting of the diaphragm aperture.

The invention has for its object to provide an aperture diaphragm with which it is possible in simple manner, at all angles of diffraction, always to illuminate the same surface of the preparation with the pencil of X-rays. It has surprisingly been found that this object can be achieved by the aperture diaphragm being so arranged to be rotatable about the centre line 7 between the diaphragm plates 1, 2 that the plane 6 of the diaphragm is always parallel to the surface of the rotatable preparation at all angles of diffraction.

With the arrangement according to the invention, a departure is made from the hitherto usual principle and it is the surface of the preparation affected by the X-ray radiation which is kept constant instead of the cross-section of the pencil of X-rays and thus instead of the primary ray intensity. As a result, with increasing angle of incidence θ , the intensity of the primary ray is increased and the decrease in intensity of the interferences with higher angles of diffraction is partially compensated for. In addition, on account of the constancy of the affected surface or area of the preparation, the number of effective crystallites remains the same and thus the fluctuations in intensity because of the crystal statistics with interferences of higher angle of diffraction 2θ are not increased.

Using such rotatable diaphragm, it is possible without any effort to measure up to the largest angles of diffraction.

tion without the diaphragm aperture itself being changed. The rotation of the diaphragm thus has the same effect as when the diaphragm is opened or closed. If the rotation of the diaphragm takes place according to the invention in complete synchronism with the θ -movement of the preparation and in fact to such an extent that the plane of the diaphragm always remains parallel to the surface of the preparation, that path of rays is always so limited by one inner edge of each plate that the same surface of the preparation is illuminated. The intensity of the X-rays incident on the preparation accordingly varies proportionally with the $\sin \theta$ with the aperture diaphragm according to the invention. Since that part of the combined polarisation, Lorentz and geometrical factor for powder exposures which is dependent on angle has the form

$$PLG = \frac{1 + \cos^2 \theta}{\sin^2 \theta \cos \theta}$$

this factor is simplified when using the diaphragm arrangement according to the invention, taking into account the diaphragm factor $B = \sin \theta$ to

$$PLBG = \frac{1 + \cos^2 \theta}{\sin^2 \theta}$$

The form of the diaphragm elements proper is of no decisive importance for the invention. In its simplest form, the diaphragm consists of two plates, which are arranged on a rotatable support. It is possible for the distance between the inner diaphragm edges to be adjustable in order to adapt the masked X-ray beam to the size of the preparation. With the rotation of the diaphragm about the centre line between the diaphragm plates, one inner edge of each plate then determines the width of the diaphragm aperture. The form of these effective diaphragm edges in their turn are dependent on the shape of the preparation to be measured. For example, if this preparation is rectangular or square, the diaphragm edges are naturally rectilinear and are situated at right angles to the plane of the diffractometer circle. However, if the preparation to be measured is round, the inner diaphragm edges are advantageously made circular in order to illuminate a large as possible surface of the preparation. As plane of the diaphragm within the terms of the invention, there is to be indicated that plane which extends between the two diaphragm plates and which also passes through the two effective diaphragm edges and through the centre line.

It is an additional advantage of the diaphragm arrangement according to the invention that those surfaces of the two diaphragm plates which are situated in the plane of the diaphragm act as an antidiiffusion screen. This applies more particularly in respect of that surface which passes through the plane of the diaphragm and which faces the secondary beam. The effective inner diaphragm edges do in fact not only limit the primary beam, but they are also the starting point of a disturbing scattered radiation. This scattered radiation is stronger as the angles of the exposed diffraction diagram are smaller. By a suitable dimension of the plate surfaces, it is thus possible according to the invention to achieve the effect that the receiver gap is screen off from the scattered radiation. This antidiiffusion screen is effective down to very small angles of diffraction, so that measurements down to a diffraction angle of about $2\theta \approx 10^\circ$ can be made.

The synchronous rotation of the diaphragm with the θ -movement of the preparation can be achieved in various ways. The movement will preferably be effected mechanically and the simplest form here is to drive the diaphragm through a toothed wheel gear.

The invention is to be more fully explained by reference to the accompanying drawing.

FIGURE 1 is a front elevational view of the diaphragm; FIGURE 2 is a side elevational view of the diaphragm;

FIGURE 3 is a sectional view taken on line 3—3 of FIGURE 1.

FIGURE 4 shows the arrangement of the diaphragm device on the diffractometer and the path of rays with an angle of diffraction 2θ .

The aperture diaphragm according to the invention consists essentially of two metal plates 1 and 2 which are disposed in juxtaposition and offset relatively to one another, each plate being provided with such an opening that together they form the window 3. This window is the diaphragm aperture proper, which can optionally be adapted to the size of the preparation by displacement of the halves of the plates. The two diaphragm plates are arranged on the rotatable support 4, which carries the gear wheel 5 at the bottom end. The plane 6 extending between the plates is designated according to the invention as the diaphragm plane, while the centre line 7 extends through the centre of the support 4 and thus of the gear wheel 5. As the X-ray beam passes through the aperture diaphragm, the width of said beam is limited by the two diaphragm edges 8 and 9 the manner in which the aperture diaphragm operates will be particularly clear by considering FIGURE 4. The aperture diaphragm is situated between the focal spot 11 of the X-ray tube and the preparation 12 in the path of rays of the diffractometer, which is represented by the diffractometer circle 10, the said diaphragm being represented in FIGURE 4 by the two effective edges 8 and 9 of the two diaphragm plates 1 and 2. The spacing of the two edges 8 and 9 from the centre line is so adjusted in this case that the preparation 12 is just fully illuminated. The preparation 12 is obviously arranged on a support similar to the support 4 of the diaphragm, so that it is in the plane of the rays. Furthermore, the preparation support also has arranged thereon a gear wheel 13, which is of the same size (diameter and number of teeth) as the gear wheel 5. The two gear wheels 5 and 13 intermesh by means of an auxiliary gear wheel 14, which is resiliently mounted by means of the spring 15, as shown in FIGURE 4.

In this way, while making the exposure of an X-ray diffraction diagram during the θ -movement of the prepara-

tion, the diaphragm plane 6 is advanced by an angle which is the same as that of the preparation 12 by the action of the gear wheels 13, 14 and 5. The plane 6 of the diaphragm thus always remains parallel to the surface 5 of the preparation. An additional effect resulting from the parallel relationship between the aperture diaphragm and the surface of the preparation is that the surfaces 16 and 17 of the two diaphragm plates lying in the diaphragm plane 6 prevents the scattered radiation emanating from the diaphragm edges 8 and 9 passing into the radiation receiver 18. The scattered rays have in fact positively not passed beyond the plane 6 of the diaphragm.

It is obvious that the shafts of the gear wheels 5, 13 and 14 must be perpendicular to the diffractometer circle and in addition the shaft of the gear wheel 5 must be adjustable perpendicularly of the primary beam in the plane of the diffractometer circle.

We claim:

1. A diaphragm arrangement for use with an X-ray diffractometer comprising:

a pair of diaphragm plates mounted on a first turntable, the turntable mounted for rotary motion on an axis between the diaphragms, a preparation plate supported for rotatable motion on a second turntable, and means for keeping the pair of diaphragm plates and the preparation plate parallel.

2. The apparatus according to claim 1 wherein the means for keeping the plates parallel comprise, first gear teeth formed about the edge of the first turntable, second gear teeth formed about the edge of the second turntable, and an idler gear in mesh with the first and second gear teeth.
